UNITED STATES PATENT OFFICE

167,663

HAIR DYE APPLICATOR

Joseph A. Voss, Denver, Colo., assignor to Gertrude S. Tenderich, Denver, Colo.

Application May 23, 1951, Serial No. 15,286

Term of patent 3½ years

(Cl. D86—10)

To all whom it may concern:

Be it known that I, Joseph A. Voss, a citizen of the United States, residing at the city and county of Denver, State of Colorado, have invented a new, original, and ornamental Design for Hair Dye Applicator, of which the following is a specification, reference being had to the accompanying drawing, forming a part thereof.

Figure 4 is a section taken on line 4—4, Fig.
1, and

I claim:

The ornamental design for a hair dye applicator, as shown.

JOSEPH A. VOSS.
